ANTISKID ATTACHMENT FOR SHOES

Guiseppe Ferrini, Bozeman, Mont.

Application September 4, 1941, Serial No. 409,566

1 Claim. (Cl. 36—7.6)

This invention relates to a novel anti-skid attachment for shoes, and more particularly to a plate adapted to be secured to a shoe sole and heel, and having serrated portions on the underside thereof which are adapted to effectively grip a slippery surface such as a surface covered with ice or snow to permit the wearer to safely walk on such surfaces.

More particularly, it is an aim of the invention to provide such an attachment having a plate portion adapted to fit the underside of a sole, including its shank portion, and to substantially correspond to the shape thereof, and to have a portion adapted to fit the underside of a shoe heel and shaped and sized to substantially correspond to the shape thereof so that the entire underside of the shoe sole and heel will be covered by the attachment.

Other objects and advantages of the invention will hereinafter become more fully apparent from the following description of the drawings, which illustrate preferred embodiments of the invention, and wherein:

Figure 1 is a side elevational view of one embodiment of the invention,

Figure 2 is a bottom plan view of the same,

Figures 3 and 4 are cross sectional views taken substantially along the planes of the lines 3—3 and 4—4, respectively, of Figure 1,

Figure 5 is a side elevational view, similar to Figure 1, of another form of the invention,

Figure 6 is a bottom plan view of the same,

Figure 7 is a side elevational view of a third form of the invention, and

Figure 7a is a section on the line 1a of Figure 5,

Figure 8 is a bottom plan view of the same.

Referring more particularly to the drawings, wherein like reference characters designate like or corresponding parts throughout the different views, and referring particularly to Figures 1 to 4, 10 designates generally a sandal type anti-skid or non-slip attachment for shoes, including a plate, designated generally 11, which is preferably formed of sheet metal, and which includes an end portion 12 which is adapted to be disposed against the underside of the half sole of a shoe and which is shaped and sized to correspond thereto. The plate 11 is provided with an intermediate portion 13 which is curved upwardly relatively to the portion 12 and which is adapted to fit against the other, shank portion of the sole and which likewise is shaped and sized to correspond thereto. The opposite end portion 14 of the plate 11 is off-set downwardly relative-

ly to the rear end of the portion 13 and is adapted to fit against the underside of the shoe heel and is shaped and sized to conform thereto. In Figure 1 the sandal 10 is shown in an applied position on a shoe which is shown in dotted lines, and designated 15. The plate 11 includes a portion 16 which is disposed substantially at a right angle to the plane thereof and which connects the portions 13 and 14 and which is adapted to be disposed against the forward side of the shoe heel.

The plate portion 12, at its forward, free end, is provided with an integral upwardly projecting portion 17 which is shaped to fit against the toe 15 of the shoe 15 to form a toe cap. The heel portion 14 is likewise provided at its rear, free end with an upwardly extending integral portion 18 which is adapted to fit around the back of the heel of the shoe. The portion 12 is provided at each side thereof with a plurality of integral upwardly extending tabs 19 forming corresponding sets of tabs adapted to be disposed on each side of the shoe 15. The shank engaging portion 13, adjacent the rear end thereof, is provided with an integral upwardly projecting tab 20 on each side thereof.

A strap 21, of flexible material, is fastened at one end thereof by means of a fastening 22 to the inner side of the toe cap 17 and extends therefrom upwardly and rearwardly over the upper part of the shoe 15, as seen in Figure 1, and is provided with spaced loops 23 and 24. A flexible member 25 is attached by means of a fastening 26, at one end thereof, to the inner side of the upturned portion 18 and extends upwardly therefrom and is adapted to be disposed against the counter of the shoe 15. The flexible member 25 is provided with a loop 27. A flexible member 28 is connected by means of fastenings 29 to the tabs 19 at one side of the plate portion 12. The flexible member 28 is provided with a restricted upper portion to which is connected a buckle 30. A strap 31 is provided with an enlarged base portion 32, which preferably corresponds in shape to the member 28 and which is adapted to be fastened to the tabs 19 at the opposite side of the plate portion 12 by means of fastenings 29. The strap 31 extends through the loop 23 and is adapted to be detachably and adjustably connected to the member 28 by means of the buckle 30 to combine with the secured end portion of the strap 21 for securing the anti-skid attachment 10 to the toe portion of the shoe 15. As best seen in Figure 3, the portions

28 and 32 are disposed on the inner sides of the tabs 19.

A strap 33 has its intermediate portion extending through the loop 27 and has corresponding portions thereof attached to the inner sides of the tabs 20 by means of the fastenings 34. One end of the strap 33 is provided with a buckle 35 and the opposite end 36 thereof is restricted and is adapted to extend through the loop 24 and over the instep of the shoe 15 and is adjustably and detachably fastened to the buckle 35 to secure the attachment 10, with the members 28, 31 and 21, securely to the shoe 15. It will be readily apparent that the toe cap 17, the portion 16 and the upturned portion 18 will prevent the plate 11 from sliding relatively to the sole of the shoe 15 and will thus combine with the straps and flexible members to prevent any relative movement of the attachment 10 relatively to the shoe 15, when applied thereto as seen in Figure 1. Furthermore, it will be readily apparent that the attachment 10 can be readily removed by detaching the straps 31 and 36 from the buckles 30 and 35, respectively.

The plate portions 12 and 14 are provided with a plurality of fold portions forming downwardly extending transversely disposed ribs 37, the bottom edges of all of which are disposed substantially in the same plane. The ribs 37 form serrations which are adapted to engage a slippery surface, such as a surface covered with ice and snow to prevent the attachment 10 from slipping relatively thereto.

The plate portions 12 and 13, as seen in Figure 2, are provided with apertures 38 for receiving driven fastenings, not shown, which are adapted to be anchored in the half sole and shank portion of the shoe, where it is desired to permanently attach the anti-skid attachment 10 to the shoe 15.

Referring to Figures 5 and 6, 39 designates generally another form of anti-skid or non-slipping device for shoes, and which comprises a plate of metal having an end portion 40 adapted to be disposed against the underside of the half sole of a shoe 15, partially shown in dotted lines in Figure 5, and which is shaped and sized to correspond thereto. The plate, forming the anti-skid device 39 includes an upwardly curved intermediate portion 41 which fits the shank of the shoe 15 and corresponds to the shape thereof. The opposite end of the plate is downwardly offset and is adapted to engage against the underside of the shoe heel and is shaped and sized to conform thereto and forms the portion 42, which is connected to the rear end of the portion 41 by means of a substantially perpendicular flange portion 43 which engages against the forward end of the heel of the shoe. The portions 40, 41 and 42 are secured to the half sole, shank and heel, respectively, of the shoe 15 by means of driven fastenings 38'. The portion 40 is punched out to form a plurality of downwardly projecting protuberances 44 which combine to form a roughened or serrated surface for the sole portion of the shoe 15. The heel portion 42, of the device 39, is provided with a plurality of fold portions forming transverse ribs 45 which are substantially V-shaped in cross section and which provide additional serrations for the heel portion of the shoe 15.

Another form of non-skidding device for shoes is shown in Figures 7 and 8, and designated generally 46. The device 46 includes a plate, designated generally 47, one end portion of which, designated 48, is adapted to fit against the underside of a half sole of the shoe 15, shown in dotted lines in Figure 7, and which is shaped and sized to conform thereto. The opposite end of the plate 47 comprises the portion 49 which fits against the underside of the shoe shank and which is likewise shaped and sized to conform thereto. The plate 47 is fastened to the half sole and shank by means of driven fastenings 50. The portion 48 at its forward, free end is provided with an upturned portion 51 which is bowed transversely to fit against the toe of the shoe 15 to form a toe cap. The portion 48 is pressed out to form a plurality of protuberances 52 which extend downwardly to provide a serrated or roughened surface for the forward part of the shoe 15. The non-slipping device 46 also includes a plate 53 which is shaped and sized to conform to the underside of the shoe heel and which is fastened thereto by means of driven fastenings 54. The plate 53 is provided with protuberances 55, corresponding to the protuberances 52 and for the same purpose, and is also provided with a fold portion forming the rib 56 which is substantially V-shaped in cross section and which is disposed near the back part of the shoe heel and diagonally thereof, to thus provide additional non-slipping means for the heel portion of the shoe 15, shown in Figure 7.

Various modifications and changes, in the embodiments of the invention as disclosed, are contemplated and may obviously be resorted to, provided they fall within the spirit and scope of the invention as hereinafter defined by the appended claim.

40 I claim as my invention:

An anti-skid attachment for shoes comprising a metal plate having portions adapted to engage against the underside of the sole, shank and heel of a shoe and substantially covering said shoe portions, the portions of the plate which engage the sole and heel having outwardly projecting, integral transverse ribs, said plate portions having integral upwardly extending tabs at the edges thereof and which are disposed across the toe of the shoe, at the sides of the sole and shank, and across the back of the heel, a flexible member attached at one end to the tab, which is disposed at the toe of the shoe, and extending upwardly along the forward part of the shoe, said flexible member having spaced loops, strap ends attached to the tabs, disposed at the sides of the sole, one of said strap ends extending through one of the loops and being detachably fastened to the other strap end, a flexible element attached to the tab, at the back of the heel, and extending upwardly therefrom, and a strap slidably connected, intermediate of its ends, to the flexible element and having complementary portions connected to the tabs, at the sides of the shank, one end of the strap extending loosely through another of the loops and being detachably fastened to the other end of the strap, and said tabs also functioning to prevent the plate from sliding longitudinally or laterally relatively to the shoe.

GIUSEPPE FERRINI.
